UNITED STATES PATENT OFFICE.

GEORGE W. SHULTZ, OF DAYTON, OHIO, ASSIGNOR TO THE DAYTON MANUFACTURING COMPANY, OF DAYTON, OHIO, A CORPORATION OF OHIO.

ATTACHMENT FOR WATER COOLERS.

Application filed March 21, 1924. Serial No. 700,944.

To all whom it may concern:

Be it known that I, GEORGE W. SHULTZ, a citizen of the United States, and resident of Dayton, in the county of Montgomery and State of Ohio, have invented certain new and useful Improvements in Attachments for Water Coolers, of which the following is a description, reference being had to the accompanying drawings, which form a part of my specification.

My invention relates to improvements in attachments for water coolers and has for its objects, first, to provide means whereby the reservoir can be drained by simply turning the faucet through which water is drawn for drinking purposes, and second, the abandonment of numerous joints and connecting parts heretofore employed to accomplish the same purpose, thus simplifying construction and materially reducing the cost of manufacture. The invention is adapted for use in connection with the water reservoir of any of various types of water coolers now in use and particularly such as are used in rail-way cars.

With the aforesaid and other objects in view, the invention consists in the various novel details of construction and combination of parts, hereinafter fully described in the specification, illustrated in the drawings and more particularly pointed out in the claims.

In the accompanying drawings forming part of the specification, and in which like characters indicate corresponding parts, I have illustrated one form of mechanism embodying the essential features of my invention, although the same may be carried into effect in other ways without in the least departing from the spirit thereof.

In the said drawings:

Figure 1 is a vertical section through the center of my improvement applied to an ordinary water cooler, showing only so much of the latter as is necessary to illustrate the application of the device to the cooler. Fig. 2 is a front view of a portion of one of the side walls of the cooler with the device attached thereto. Fig. 3 is a reduced perspective view of a portion of the body of the cooler. Fig. 4 is a side view, partially in section, of the valve fitting showing the opposite side from that shown in Figure 1, and showing the valve plug in position for draining the cooler.

Referring to the drawings A represents a water cooler, which for the purpose of illustration I have shown square, in cross section, with four walls, 1, 2, 3 and 4, but which may be of any desired contour suitable to the place in which the cooler is to be installed, and a single continuous wall may be substituted for the four walls shown. B represents a water reservoir or chamber formed by and within the said walls and having a bottom plate C which is secured to the same at a suitable distance above the bottom thereof, providing an open space D therebelow. The top of the cooler, which may be of any desired height, is provided with the usual removable cover for filling the reservoir with water, the bottom being designed to rest upon a suitable support. An exteriorly screw threaded flanged nipple 5 passes through and is secured to the plate C in open communication with the reservoir B. A valve casing E comprising a body member 6 having a tapered horizontal bore 7 and hollow extending members 8—9—10 is coupled, at 8, to the nipple 5 through which communication is established between the reservoir, the valve casing and the said hollow extending members. In the tapered bore of the casing there is fitted a correspondingly tapered plug F having a chamber 11 and being held in place by the customary screw and washer arrangement common to valves of similar construction. The wall 1 of the cooler is perforated to receive a bushing 12 having a flange 13 which is secured to the said wall. Connected to the valve plug, at its free or larger end, and opening into the chamber 11 there is a horizontally disposed tubular member 14 which extends through and beyond the bushing 12 to receive a faucet G, exteriorly and interiorly screw threaded means being preferably employed for connecting the valve plug with the faucet, as clearly shown in Figure 1, it being obvious, however, that my invention does not contemplate any specific means for connecting these parts together, nor does it contemplate any specific type of valve or faucet as any of the various types suitable for the purpose may be employed, those illustrated in the drawings being selected as most desirable.

In further description of the faucet G, 15 represents its casing having a flange member 16 the inner face of which adjoins the 110

outer face of the flange 13 of the bushing 12 and around which the faucet is adapted to rotate, as and for a purpose presently to be explained. Within the faucet casing G there is formed a water passage 17 which communicates with the reservoir B, through the tubular member 14; the valve plug F; the casing E, and the nipple 5, whereby, when the parts are in normal position, as shown in Figure 1, water may be drawn from the reservoir through a nozzle 18 having an outlet channel 19 in open communication with the passage 17, the flow of water through the faucet being controlled by means of a spring actuated valve 20 mounted on and secured to a movable rod 21 and co-acting with a valve seat 22 formed on the inside of the casing, the rod 21 being supported in bearings 23—24, and the valve being forced against its seat by means of a coiled spring 25 located between the valve and the bearing 23, which is secured to the casing. The outer or free end of the faucet terminates in a hollow extension 26 forming a chamber 27 within which operates a push piece 28 secured to the end of rod 21 and which when pressed inwardly will open the valve and permit water to flow from the reservoir B through a series of openings 29 in the bearing 23, to and out of the nozzle 18, passing in its course through openings 30 and 31 in the valve plug F, as indicated by arrows in Figure 1. Referring again to the flange 13 of the bushing 12, this flange has an extension 32 which is provided with a laterally projecting member 33 having a bored chamber 34 projecting inwardly through the wall of the cooler into the space D, within this chamber there is mounted a movable bolt 35 having a reduced shank 36 forming a shoulder 37 and extending through the bottom wall 38, the free end of the shank being upset to prevent removal of the bolt from the chamber, the large or forward end of the bolt projects a suitable distance beyond the face of the extension 32 and a spiral spring 40 is interposed between the shoulder 37 and the bottom wall 38, the function of the spring being to force the bolt forward into engagement with an extended portion 41, of the flange member 16 of the faucet G and which is bifurcated, as shown, at 42, to receive the bolt. Thus the faucet, together with the valve plug and the connecting member 14, are held against undue rotation, it being understood that the member 14 is rotatable in the bushing 12.

To the member 10 of the valve casing E there may be connected a suitable drain pipe 60 to carry off the water from the reservoir B when it is desired to drain the same, which operation is accomplished by rotating the faucet G a quarter turn, in the direction indicated by the arrow, and to the position shown by dotted lines in Figure 2. To do

this the operator, by the aid of any suitable instrument, presses back the bolt 35 to clear the inner surface of the extended member 41 of the flange 16, when the faucet will be free to be turned as aforesaid and when so turned the flow of water from the reservoir B will be cut off from passage to the faucet by means of the opening 30, through the wall of the valve plug, being shifted to the position shown in Figure 4, and when in this position oppositely disposed openings 43—44 are brought into direct communication with the reservoir B and through said openings its contents will be emptied, and complete drainage of the same accomplished through channels 47 formed in the flange of the nipple 5, as shown in Figure 1. The member 9 of the valve casing E is cut away at 45 and this cut away portion in cooperation with a stop lug 46, driven into the valve plug, regulates the rotative movement of the latter, in the manner common to fittings of this character.

Having thus fully described my invention and without limiting the same to the within specific details of construction as covering the scope thereof—

I claim:

1. In attachments for water coolers, the combination with a reservoir adapted to contain water, of a valve located below the bottom of the reservoir and being in communication therewith, a movable faucet casing located outside of the cooler adjacent one of the walls thereof and having mechanism therein for controlling the flow of water therethrough, means for connecting the valve with the faucet whereby water will flow through said valve to and through said faucet, and mechanism adapted to operate said valve by movement of said faucet.

2. In attachments for water coolers, the combination with a reservoir adapted to contain water, of a valve located below the bottom of the reservoir and being in communication therewith, a movable faucet casing located outside of the cooler adjacent one of the walls thereof and having mechanism for controlling the flow of water therethrough, means for connecting the valve with the faucet whereby water will flow through said valve to and through said faucet, mechanism adapted to operate said valve by movement of said faucet, and a locking device adapted to secure the faucet against undue movement thereof.

3. In attachments for water coolers, the combination with a reservoir adapted to contain water, of a valve located below the bottom of the reservoir and being in communication therewith, a faucet casing located outside of the cooler adjacent one of the walls thereof and having mechanism therein for controlling the flow of water therethrough, and rotative means extending through said

wall connecting the valve with the faucet, whereby water will flow through the valve to and through the faucet and whereby opening and closing of the valve is accomplished by partial rotation of the faucet.

4. In attachments for water coolers, the combination with a reservoir adapted to contain water, of a valve located below the bottom of the reservoir and being in communication therewith, a faucet casing located outside of the cooler adjacent one of the walls thereof and having mechanism therein for controlling the flow of water therethrough, rotative means extending through said wall connecting the valve with the faucet, whereby water will flow through the valve to and through the faucet and whereby opening and closing of the valve is accomplished by partial rotation of the faucet, and a locking device adapted to secure the faucet casing against undue movement thereof.

5. In attachments for water coolers, the combination with a reservoir adapted to contain water, of a valve located below the bottom of the reservoir and being in communication therewith, a flanged bushing secured to and extending through one of the walls of the cooler, a faucet located outside of the cooler adjacent the said flanged bushing, and a member connecting said faucet and said valve; said member being movable in said bushing and having a water passage therethrough, whereby opening and closing of the valve is accomplished by movement of the faucet.

6. In attachments for water coolers, the combination with a reservoir adapted to contain water, of a valve located below the bottom of the reservoir and being in communication therewith, a flanged bushing secured to and extending through one of the walls of the cooler, a faucet located outside of the cooler adjacent the said flanged bushing, a member connecting said faucet and said valve; said member being movable in said bushing and having a water passage therethrough, whereby opening and closing of the valve is accomplished by movement of the faucet, and a locking device adapted to secure the faucet against undue movement thereof.

7. In attachments for water coolers, the combination with a reservoir adapted to contain water, of a valve located below the bottom of the reservoir and being in communication therewith, a movable faucet located outside of the cooler adjacent one of the walls thereof, and means connecting said valve with said faucet whereby when the faucet is in its normal position water will flow from the reservoir through the valve to the faucet and when moved to another predetermined position the flow of water to the

faucet will be cut off and will pass through the valve to discharge the contents of the reservoir and drain the cooler.

8. In attachments for water coolers, the combination with a reservoir adapted to contain water, of a valve located below the bottom of the reservoir and being in communication therewith, a movable faucet located outside of the cooler adjacent one of the walls thereof, means connecting said valve with said faucet whereby when the faucet is in its normal position water will flow from the reservoir through the valve to the faucet and when moved to another pre-determined position the flow of water to the faucet will be cut off and will pass through the valve to discharge the contents of the reservoir and drain the cooler, and a locking device adapted to secure the faucet against undue movement thereof.

9. In attachments for water coolers, the combination with a reservoir adapted to contain water, of a valve located below the bottom of the reservoir and being in communication therewith, a flanged bushing secured to and extending through one of the walls of the cooler, a faucet located outside of the cooler adjacent the said flanged bushing, and a member connecting said faucet and said valve; said member being movable in said bushing and having a water passage therethrough, whereby when the faucet is in its normal position water will flow from the reservoir through the valve to the faucet and when moved to another predetermined position the flow of water to the faucet will be cut off and will pass through the valve to discharge the contents of the reservoir and drain the cooler.

10. In attachments for water coolers, the combination with a reservoir adapted to contain water, of a valve located below the bottom of the reservoir and being in communication therewith, a flanged bushing secured to and extending through one of the walls of the cooler, a faucet located outside of the cooler adjacent the said flanged bushing, a member connecting said faucet and said valve; said member being movable in said bushing and having a water passage therethrough, whereby when the faucet is in its normal position water will flow from the reservoir through the valve to the faucet and when moved to another predetermined position the flow of water to the faucet will be cut off and will pass through the valve to discharge the contents of the reservoir and drain the cooler, and a locking device adapted to secure the faucet against undue movement thereof.

In testimony whereof I affix my signature hereto.

GEORGE W. SHULTZ.
